DESIGN FOR A MATCH FOLDER

John H. Lewis, Washington, D. C.

Application June 17, 1936, Serial No. 63,340

Term of patent 14 years

To all whom it may concern:

Be it known that I, John H. Lewis, a citizen of the United States, residing at Washington, in the District of Columbia, have invented a new, original, and ornamental Design for a Match Folder of which the following is a specification, reference being had to the accompanying drawing, forming part thereof.

Figure 1 is a perspective view of the match folder showing my new design, the cover being open and the flap in closed position; and

The dominant feature of my design resides in the ornamental flap.

I claim:—

The ornamental design for a match folder as shown and described.

JOHN H. LEWIS.
